(57) **CLAIM**

The ornamental design for a “document tray,” as shown and described.

DESCRIPTION

FIG. 1 is a perspective view of a document tray showing our new design;

FIG. 2 is a front elevational view of the document tray of FIG. 1;

FIG. 3 is a left side elevational view of the document tray of FIG. 1, the right side elevational view being a mirror image thereof;

FIG. 4 is a rear elevational view of the document tray of FIG. 1;

FIG. 5 is a top plan view of the document tray of FIG. 1; and, FIG. 6 is a bottom plan view of the document tray of FIG. 1.

The dashed lines are for illustrative purposes only and form no part of the claimed design.

1 Claim, 3 Drawing Sheets
